Cooking Stoves and Ranges.

Des. 274

Samuel A. House of Mechanicville N.Y.
Letters Patent No. 274. Dated March 26th 1850

The schedule referred to in these Letters Patent and making part of the same.

To all whom these presents shall come:

Be it known that I, Sam'l A. House, of Mechanicville, in the County of Saratoga, and State of New York, have invented or produced a new design of Cooking Stove, which I call the "Saratoga County air tight"; and I do hereby declare that the following is a full, clear and exact description of the same, reference being had to the annexed drawings which make a part of this specification, it being a perspective view of the whole stove, with the exception of the hearth or summer arrangement, and one of the front doors, the door being the same design or pattern as that represented on the front.

My stove is in the usual form of a square Cooking Stove, with rounded corners, the ornaments mainly being on the doors, which are surrounded by deep mouldings, on the most projecting part of which there are raised diamond shaped ornaments, intersected with small beads as represented, forming in the central part panels on which are arranged arabesque ornaments, consisting of flower, leaf, and scroll work as represented at a, a, a, a; and also small ornaments b, b, on the sides.

The rounded corners forming in a manner a panel surrounded by the mouldings c, c, and bordered by bead ornaments d, d. The stove is supported on arabesque ornamented feet e, e.

What I claim as my new design and desire to secure by Letters Patent, is the design and configuration of the ornaments so disposed on the doors, feet, and other parts of the stove, constituting in combination a new design of cook stove the same as herein described and represented.

Witnesses,

End C. L. Brundage }
